UNITED STATES PATENT OFFICE.

ARTHUR W. COLEN, OF PHILADELPHIA, PENNSYLVANIA, ASSIGNOR TO ARTCO ADVERTISING, INC., OF PHILADELPHIA, PENNSYLVANIA, A CORPORATION OF PENNSYLVANIA.

SUBSTITUTE FOR METAL.

Application filed April 19, 1928. Serial No. 271,230.

Hammered metal, and specifically hammered wrought iron, is considered as being artistic and has been adopted for all sorts of decorative purposes. It has been used in 5 the decoration of homes, in big buildings, in hotels and apartment houses and in store window displays. It has been used for gates, for window lattices, for floor lamps and in as many other shapes and forms as 10 the fancy of the artist, architect or interior decorator dictated.

In many instances its use is desirable but is not advisable because of the cost. The 15 present invention relates particularly to a substitute for this product and a method of making the same, which product, while simulating the same artistic effects as that produced by the hammered metal product, is, nevertheless, much cheaper.

20 An object of this invention is to produce a method of manufacturing substitutes for hammered metal products.

Another object of this invention is to produce a method of manufacturing imitation 25 hammered metal products.

Another object of this invention is to produce a method of manufacturing substitutes for hammered wrought iron products.

Another object of this invention is to produce 30 substitutes for hammered metal products.

Another object of this invention is to produce substitutes for hammered wrought iron.

These and other objects of this invention 35 will become more evident from the following description and drawings.

In the drawings, Figure 1 denotes a piece of material before work is commenced thereon to make the article desired.

40 Figure 2 illustrates the first step—cutting the stock to the shape desired and shows the article desired after it has been cut out of the stock material.

Figure 3 illustrates the second step—hammering—and shows the article after it has been hammered.

45 Figure 4 illustrates the third step, viz—the primary coating process—and shows the article with the primary coat of paint applied.

Figure 5 illustrates the fourth step, viz—the secondary coating process—and shows the article with the secondary coat of paint applied.

50 Figure 6 illustrates the final step—viz—

abrading—and shows the final product after the abrasive has been applied.

Referring more specifically to the figures and the method of making the same, reference numeral 1 refers to a piece of stock 60 which may be of wood, compos board, board made from fibrous material, or any other material which is adapted to be cut with comparative ease and herein generically designated as "sheet material". This stock 65 is then cut into the shape of the article which is desired, as shown at 2. The article is now hammered with a rounded hammer, producing indentations 3 resembling those of hammered metal. The indentations 3 may also 70 be produced by cutting with a suitable tool. Then the article is cut with a suitable tool to produce ornamentations 6 if ornamentation effects are desired. Then a primary coat of paint 4 is applied over the entire surface. This paint is of such a color that after treatment it gives one of the color effects produced by the hammered metal. For instance, in making a substitute for hammered wrought iron, the first coat is silver; then, 75 80 a secondary coat of paint 5 is applied over the entire surface. The paint of this coat is of such a color that it gives another of the color effects produced by the hammered metal. Although in most cases only two 85 coats are necessary, more coats may be used to produce the color effects desired. The article is then rubbed with an abrasive such as sandpaper, emery cloth, or the like. This removes most of the dark color from the 90 high spots, but leaves it in the low. In addition, bits of dark color are left and blend in with the light color of the primary coat which has been either wholly, or partly exposed as a result of the treatment with the 95 abrasive. This blend combines with the dark color in the low spots to produce the same effect as that of the metal which is being imitated.

For instance, in making a substitute for 100 hammered wrought iron, the wood, or other material which is to be used as a base, is cut to the design desired, it is then hammered and decorated, if decoration is desired. The primary coat of silver paint is then applied. 105 This is followed by the secondary coat of black. It is then rubbed with sand-paper to the point where the article gives the exact color effect desired.

In making a substitute for hammered 110

brass, the article is first cut to shape, hammered and ornamented as above outlined. Then a coat of gold paint is applied. This is followed by a coat of deep bronze. This is then followed by abrading.

The above disclosure is by the way of illustration only and not by the way of limitation. By the above outlined process, substitutes for any metal desired may be made.

Having described my invention, what I claim as new and useful is:—

1. The method of manufacturing substitutes for hammered metal which consists in forming a piece of material to the shapes desired, then treating it to make surface depressions, then painting the same with a primary coat of paint, then painting the same with a secondary coat of paint, finally rubbing the device with an abrasive.

2. The method of manufacturing substitutes for hammered metal which consists in cutting a piece of suitable material to the shape desired, then pounding it to make sur-

face depressions, then painting the same with a primary coat of paint, then painting the same with the secondary coat of paint, and, finally, rubbing the same with an abrasive.

3. The method of manufacturing substitutes for hammered metal which consists in cutting a piece of suitable material to the shape desired, then pounding it to make surface depressions, then cutting ornamental designs thereon, then coating the same with a primary coat of paint, then coating the same with a secondary coat of paint, and, finally, rubbing the same with an abrasive.

4. A substitute for hammered metal products comprising articles cut from sheet material, the said articles having depressed and undepressed surfaces therein, paint covering the said depressed surfaces, paint covering the said undepressed surfaces, the said paint being of a plurality of color tones.

In testimony whereof, I affix my signature.

ARTHUR W. COLEN.
